United States Patent Office

Des. 178,862
Patented Oct. 2, 1956

178,862

CURTAIN RING

Francis E. Blod, Tuckahoe, N. Y., assignor to Joseph A. Kaplan & Sons, Inc., New York, N. Y., a corporation of New York

Application July 12, 1955, Serial No. 36,922

Term of patent 14 years

(Cl. D21—1)

Figure 1 is an obverse elevational view of a curtain ring embodying my new design, the curtain ring being shown in closed condition;

Figure 2 is a side view;

Figure 3 is a bottom view;

Figure 4 is a reverse elevational view;

Figure 5 is a top view;

Figure 6 is a cross-sectional view along the line 6—6 of Figure 1; and

Figure 7 is a view like Figure 1, showing the curtain ring in opened condition.

I claim:

The ornamental design for a curtain ring, substantially as shown and described.
